UNITED STATES PATENT OFFICE.

CLYDE J. COLEMAN, OF NEW YORK, N. Y., ASSIGNOR TO THE HALL SIGNAL COMPANY,
A CORPORATION OF MAINE.

TRAFFIC-CONTROLLING SYSTEM FOR RAILROADS.

1,025,371.

Specification of Letters Patent.

Patented May 7, 1912.

Application filed July 7, 1908. Serial No. 442,320.

To all whom it may concern:

Be it known that I, CLYDE J. COLEMAN, a citizen of the United States, residing in the borough of Manhattan, city of New York, 5 in the county of New York and State of New York, have invented a certain new and useful Improvement in Traffic-Controlling Systems for Railroads, of which the following is a specification, reference being had 10 therein to the accompanying drawings, forming part thereof.

My invention relates to electric traffic-controlling systems for railroads.

The invention is particularly applicable 15 to electric signal systems of the automatic type, but is adapted also, in its broadest sense, to the operation of switches and other traffic-controlling devices.

The object of the invention is to produce 20 a simple traffic-controlling system and to secure economy in the expenditure of electric energy.

In automatic electric traffic-controlling systems it is customary to provide for the 25 operation of the apparatus, in accordance with the position and movements of a train, by means of electric circuits energized by a source of current extraneous to the train and controlled by or from the train.

30 In the present invention I employ the novel principle of controlling the electric apparatus by means of electric energy transmitted from the train itself direct to the track rails, and in this way I attain a simplicity in construction and operation, and an economy in expenditure of electric energy, which will be apparent from a consideration of the particular application of this principle herein-after described.

40 I will now describe the illustrated embodiment of the invention, and will thereafter point out the invention in claims.

The drawing shows two complete signaling blocks of a railway track, with portions 45 of the two adjacent blocks, and the three signal stations are designated, respectively, as A, B and C.

In the illustrated embodiment of the invention the track rails 1 are continuously 50 conductive and constitute portions of track circuits. At the ends of the blocks are transformers, of which the primary windings 2 are connected across the track rails, while the secondary windings 3 are connect-

55 ed with the magnets 4 of track relays by

which the local signal circuits are controlled. Each relay has a contact finger 5 and the contact finger is in local circuit with the signal 6 and the signal battery 7. The signal has a normal bias to danger, but is provided with a suitable motor, which may be of any ordinary or suitable form and is not shown, by which the signal is cleared when the local signal circuit is closed by the action of contact finger 5. In the normal condition of the apparatus, which is illustrated at A and B, the transformer is deenergized, the contact finger of the relay is in open-circuit position, and the signal stands at danger.

The current by which the transformer is energized to cause the relay to close the local signal circuit and clear the signal is transmitted through the track rails from the approaching train itself. For this purpose the train is provided with an inductive coil carried ahead of the foremost wheels and close to the rails. Two trains 8 and 9 are illustrated in blocks B-C and A-B, respectively. Each train is provided with an inductive coil 10 in advance of the foremost wheels 12, and the coil is connected with a suitable alternating generator 11 carried by the train. This generator is constantly in operation during the running of the train, and the alternating current in coil 10 acts inductively on the track rails and induces a current in the track, ahead of the train. This current follows a circuit comprising the two track rails, the foremost wheels 12 with their axle and, under normal conditions, the primary winding 2 of the transformer at the signal station next in advance. As the rails are continuously conductive, a portion of the current will also be diverted to the transformers at stations farther in advance, but not sufficiently to materially detract from effectiveness of the current in the first transformer in advance of the train, and, as the train nears the end of 100 the block the current in said first transformer becomes strong enough to operate the relay and clear the signal in advance of the train. This normal operation of the apparatus is illustrated at C, where current from coil 10 on train 8 has energized the transformer and the relay, and the signal circuit through signal 6 is closed and the signal cleared.

When the block next in advance of a sig- 110

nal is occupied, the signal cannot be cleared, for the reason that the wheels and axles of the train, ahead afford an alternative path for currents in the track circuit which is 5 of such low impedance relative to that of the transformer that the amount of current flowing through the transformer is insufficient to actuate the relay. This condition is illustrated at B. Train 9, which is approaching B, is unable to clear the signal there, because the current induced by coil 10 on train 9 passes for the most part through a circuit comprising the rails, wheels 12 and their axle on train 9, and the 15 rearmost wheels 13 and their axle on train 8, only a small portion of the current flowing through the transformer at B. Signal B therefore remains at danger until train 8 passes out of block B-C.

20 All of the circuits of this system are normally deenergized, and there is no expenditure of energy except in energizing the inductive coil on the train itself. As it is unnecessary to energize the track circuit until 25 the train nears the end of the block, a further economy may be effected by cutting out the inductive coil while the train traverses the first part of the block.

Although in the invention is illustrated 30 as applied to a very simple system in which only home signals are employed, it will be obvious that it may be applied, with advantage, to many other systems, and that various modifications may be made in the embodiment of the invention hereinbefore described and illustrated in the accompanying drawing, within the nature of the invention and the scope of the following claims.

I claim:

40 1. A traffic-controlling system comprising, in combination with track rails and a car, traffic-controlling means located at a fixed point along the track and electrically connected to the track rails, a conductor carried by the car in inductive relation to the rails for inducing electromotive force in the rails to produce therein electric current to operate the traffic-controlling means, and means for generating current in said conductor.

45 2. A traffic-controlling system comprising, in combination with track rails and a car, traffic-controlling means located at a fixed point along the track and electrically connected to the track rails, a conductor carried by the car in inductive relation to the rails for inducing electromotive force in the track rails in advance of the car to produce therein electric current to operate the traffic-controlling means, and means for generating 55 current in said conductor.

60 3. A traffic-controlling system comprising, in combination with track rails and a car, traffic-controlling means located at a fixed point along the track, electric controlling means therefor connected with the track

70 rails, a conductor carried by the car in inductive relation to the rails for inducing electro-motive force in the track rails to produce therein electric current in advance of the car to operate said electric controlling means, and means for generating current in said conductor.

75 4. A traffic-controlling system comprising, in combination with track rails and a car, traffic-controlling means located at a fixed point along the track, transformers in control thereof and connected with the track rails, a conductor carried by the car in inductive relation to the rails for inducing electro-motive force in the track rails to produce therein electric current to energize the 80 transformers, and means for generating current in said conductor.

85 5. A traffic-controlling system comprising, in combination with track rails and a car, traffic-controlling means located at a fixed point along the track and electrically connected to the track rails, a coil carried by the car in inductive proximity to the rails, and means for energizing the coil to induce electro-motive force in the track rails to produce 90 therein current for the purpose of operating the traffic-controlling means.

95 6. A traffic-controlling system comprising, in combination with track rails and a car, traffic-controlling means, inductive apparatus connected with the traffic-controlling means and the rails, inductive apparatus carried by the car in inductive relation to the track rails, and means for energizing the latter to induce electro-motive force in the track rails to produce therein current to operate the traffic-controlling means.

100 7. A traffic-controlling system comprising, in combination with track rails and a car, traffic-controlling means located at a fixed point along the track and controllable by the condition of the track ahead and adapted to indicate the condition of such track, and means carried by the car and acting directly upon the track rails for transmitting an electric current through the rails to control the operation of the traffic-controlling means.

105 8. A traffic-controlling system comprising, in combination with track rails and a car, traffic controlling apparatus located at a fixed point along the track, electric controlling means therefor connected to the track rails, and means carried by the car for producing a difference in potential between the two rails at a point in advance of the car to produce in the rails a current flowing in opposite directions in the two rails and operative to control the electric-controlling means.

110 9. A traffic-controlling system comprising, in combination with track rails and a car, traffic-controlling apparatus arranged to normally give a danger indication, electric 115

- controlling means for the traffic-controlling apparatus having electrical connection with the track rails, and means carried by the car for producing a difference of potential 5 between the two rails at a point in advance of the car to produce in the rails a current flowing in opposite directions in the two rails and operative to control the electric controlling means.
- 10 10. A traffic-controlling system comprising, in combination with track rails and a car, traffic-controlling apparatus located at a fixed point along the track and arranged to normally give a danger indication, electric 15 controlling means for the traffic-controlling apparatus having electrical connection with the track rails, and means carried by the car for producing a difference of potential between the two rails at a point 20 in advance of the car to produce in the rails

a current flowing in opposite directions in the two rails and operative to control the electric controlling means.

11. A traffic-controlling system comprising, in combination with track rails and a car, traffic-controlling apparatus having electrical connection with the track rails and arranged to indicate the condition of the track ahead and controllable by the condition of such track, and means carried by 25 the car for inducing electro-motive force in advance of the car to produce a current in the rails to control the traffic-controlling apparatus.

In testimony whereof I have affixed my 30 signature in presence of two witnesses.

CLYDE J. COLEMAN.
